UNITED STATES PATENT OFFICE

124,743

DESIGN FOR A DISPLAY STAND FOR ARTICLES OF MERCHANDISE

Paul M. Kleinwachter, Chicago, Ill.

Application December 6, 1939, Serial No. 88,715

Term of patent 14 years

To all whom it may concern:

Be it known that I, Paul M. Kleinwachter, a citizen of the United States, residing at Chicago, in the county of Cook and State of Illinois, have invented a new, original, and ornamental Design for a Display Stand for Articles of Merchandise, of which the following is a specification, reference being had to the accompanying drawing, forming a part thereof.

Fig. 1 is a front perspective view of the display stand for articles of merchandise, showing my novel design.

Fig. 2 is a side elevational view of the display stand on a reduced scale.

Fig. 3 is a top plan view of the display stand on a reduced scale.

Fig. 4 is a reduced scale rear elevational view of the display stand.

I claim:

The ornamental design for a display stand for articles of merchandise, substantially as shown.

PAUL M. KLEINWACHTER.
